PATENTED AUG. 20, 1907.

G. H. WHEARY.

SKIRT AND TROUSERS HANGER.

APPLICATION FILED MAY 16, 1907.

UNITED STATES PATENT OFFICE.

GEORGE H. WHEARY, OF RACINE, WISCONSIN, ASSIGNOR TO THE HARTMANN TRUNK CO., OF RACINE, WISCONSIN.

SKIRT AND TROUSERS HANGER.

No. 864,114.

Specification of Letters Patent.

Patented Aug. 20, 1907.

Application filed May 16, 1907. Serial No. 373,930.

To all whom it may concern:

Be it known that I, GEORGE H. WHEARY, a citizen of the United States, residing at Racine, in the county of Racine and State of Wisconsin, have invented a new 5 and useful Skirt and Trousers Hanger, of which the following is a specification.

This invention relates to garment hangers of that general class especially designed for supporting trousers, skirts and other articles of wearing apparel so as to 10 retain the garments in proper shape and prevent the same from creasing or wrinkling when not in use.

The object of the invention is to provide a rack or hanger including a support having a plurality of clamping members pivotally mounted for swinging 15 movement thereon and adapted to clamp the garment to be supported whereby said garment may be suspended by one end from the support.

A further object is to provide means for limiting the swinging movement of the clamping members or bails 20 and means for suspending the hanger from a rod or other suitable support.

A still further object of the invention is to generally improve this class of devices so as to increase their utility, durability and efficiency.

25 Further objects and advantages will appear in the following description, it being understood that various changes in form, proportions and minor details of construction may be resorted to within the scope of the appended claims.

30 In the accompanying drawings forming a part of this specification: Figure 1 is a perspective view of a garment hanger constructed in accordance with my invention. Fig. 2 is a vertical sectional view of the same. Fig. 3 is a plan view of a modified form of the 35 invention. Fig. 4 is a similar view illustrating a further modification.

Similar numerals of reference indicate corresponding parts in all of the figures of the drawings.

The improved garment hanger forming the subject 40 matter of the present invention includes a substantially rectangular frame or support comprising spaced longitudinal bars 5 having their opposite ends interposed between parallel end pieces or standards 6 and 7 and rigidly secured thereto by screws, nails or similar fastening devices 8. Extending vertically of the frame between the end pieces or standards are intermediate standards or braces 9 and 10 which serve to divide the frame or support into two sections each of which is provided with a plurality of pivoted clamping members or 45 bails 11. The bails 11 are each preferably formed of a single piece of wire having their opposite ends bent to form angularly extending arms 12 the terminals of which are bent laterally to form pivot points or lugs 13 which engage suitable sockets 14 in the brackets 15, as

shown. The clamping members or bails 11 of each section of the rack are pivotally mounted for swinging movement between the longitudinal bars 5 of the rack and are movable into engagement with the exposed face of the adjacent bar thereby to clamp the garment 16 in engagement with the bar, as best shown in Fig. 1 of the 55 drawings.

Attention is here called to the fact that the swinging movement of the clamping members 11 is limited by engagement of the arms 12 with the adjacent longitudinal edges of the bars 5 thus retaining the clamping 60 members in convenient position to engage the garment. The braces or standards 6 and 10 are preferably extended beyond the upper longitudinal edge of the adjacent bar 5 to form supports or brackets 17 similar in construction to the brackets 16 and adapted to support the upper clamping member or bail of each section of the rack. Secured to the upper longitudinal bar of the rack are spaced suspension devices 18 each having one end thereof bent to form an eye 19 for the reception of a securing bolt 20 while the opposite end thereof terminates 70 in a downwardly extending hook 21 which engages a ring or loop 22 slidably mounted on a rod or other suitable support, indicated at 24. Interposed between the eye 19 and the adjacent head of the securing bolt 20 is a disk or washer 25 which serves to prevent the eye from 75 becoming accidentally detached from the securing bolt 20, there being suitable guides or keepers 26 secured to the bar 5 above the eyes 25 and engaging the suspension devices 18 to assist in retaining the latter in position on the rack.

85 It will here be noted that the rearward swinging movement of the upper clamping member or bail of the rack is limited by engagement with the adjacent suspension device 18.

The longitudinal bars forming the body of the rack 90 are preferably reinforced and strengthened by constructing the same of a plurality of strips of wood with the grain running in opposite directions so as to prevent the same from splitting or cracking when subjected to the weight of the trousers or other garments supported by 95 the rack.

In using the device the clamping members or bails 11 are tilted upwardly out of contact with the adjacent longitudinal bars 5 and one end of the trousers passed downwardly over the bail and between the latter and the adjacent longitudinal bar 5, the weight of the trousers causing the bail to bear against the rack or support and thus clamp the trousers in engagement therewith.

105 In order to remove the trousers it is merely necessary to exert a slight upward pressure on the clamping members when the trousers may be readily detached from the latter, as will be readily understood.

The device shown in Fig. 1 of the drawings is principally designed for supporting or suspending a plurality of pairs of trousers. In Fig. 3 of the drawings, however, there is shown a modified form of the invention especially designed for supporting a single pair of trousers. In this form of the device the opposite end braces or standards 6' are extended vertically beyond the body of the rack to form supports for the brackets 15' which in turn support the pivoted clamping member or bail 11', 10 as shown.

A further modification is illustrated in Fig. 4 of the drawings in which the intermediate braces or standards 9 and 10 are dispensed with, the clamping members or bails 11" being extended the entire length of the rack 15 so as to form a convenient support for a skirt or other lady's garment, indicated at 27.

The rod 24 may be secured to a wall or arranged within a closet or ward-robe so that one or more of the garment hangers or racks may be suspended therefrom.

20 The devices may be made in different sizes and shapes and provided with any number of clamping members for engagement with the garments.

From the foregoing description it will be seen that there is provided an extremely simple, inexpensive 25 and efficient device admirably adapted for the attainment of the ends in view.

Having thus described the invention what is claimed is:

1. A garment hanger including a support having longitudinal bars spaced apart to form an intermediate recess, 30 and a clamping member pivotally mounted for swinging movement at said recess and adapted to engage a garment the upward swinging movement of the clamping member

being limited by engagement with the adjacent longitudinal bar.

2. A garment hanger comprising a support including spaced longitudinal bars, clamping members pivotally mounted for swinging movement between the bars and adapted to engage a garment, the upward swinging movement of the clamping members being limited by engagement with the lower longitudinal edges of the adjacent bars. 40

3. A garment hanger comprising a support including spaced longitudinal bars connected by terminal and intermediate braces, brackets secured to said braces, and clamping members pivotally mounted in the brackets between said bars and adapted to engage the garment. 45

4. A garment hanger comprising a support including spaced longitudinal bars connected by end braces, a transverse brace secured to the intermediate portions of the 50 bars, and a plurality of superposed clamping members pivotally mounted for swinging movement on the intermediate and terminal braces of the rack for engagement with a garment, said clamping members being disposed on each side of the intermediate brace. 55

5. A garment hanger including a support, a clamping bail pivotally mounted on the rear of the support and provided with angularly disposed arms extending over and bearing against the top of the support, and a suspension device secured to the support. 60

6. A garment hanger including a frame, brackets secured to the frame and provided with sockets, a clamping bail having laterally extending lugs for engagement with the sockets of the brackets, said bail being provided with angularly disposed arms extending over the top of the frame. 65

In testimony that I claim the foregoing as my own, I have hereto affixed my signature in the presence of two witnesses:

GEORGE H. WHEARY.

Witnesses:

CLINT D. FRAZELL,
MAX BLOCH.
